UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMPING SYSTEM.

1,425,928.

Specification of Letters Patent. Patented Aug. 15, 1922.

Application filed July 27, 1917. Serial No. 183,097.

To all whom it may concern:

Be it known that I, BURTON S. AIKMAN, a citizen of the United States, residing at Milwaukee, in the county of Milwaukee and 5 State of Wisconsin, have invented a certain new and useful Improvement in Pumping Systems, of which the following is a full, clear, concise, and exact description, reference being had to the accompanying drawings, forming a part of this specification.

My invention relates to pumping systems and more particularly to systems of the class in which the pump is submerged in the water of the well or other source of supply 15 and discharges into a consumption system such as the pipes and faucets of a dwelling or the like, the opening and closing of the faucets controlling starting and stopping of the pump.

20 Pumps of this class are generally operated upon compressed air. Heretofore it has been customary to control the admission and exhaust of the compressed air to and from the pump cylinder by means of 25 float controlled valves located within the pump cylinder or cylinders at the foot of the well.

According to the present invention the controlling valves are placed at the head of 30 the well.

Heretofore it has been customary to employ a double cylinder pump for obtaining a steady flow in the consumption system. According to my invention I provide what is 35 known as "an air spring" for smoothing out the inequalities in flow in the consumption system caused by the intermittent strokes of the single cylinder pump.

My invention further provides for a combined use of this air spring with the controlling valves for operating the pump. Instead of employing a float control valve in the pump cylinder itself at the foot of the well, I employ a float valve in the air spring 45 which is operated by the rise and fall of the level of water in this air spring for admitting and exhausting air to and from the pump.

This level control valve may operate to 50 control the compressed air directly or may operate through relay means for controlling the working of the pump.

In order to advise those skilled in the art how to practice my invention I shall describe the same in connection with the ac-

companying drawings which form a part of the present specification, illustrating a specific embodiment in which the invention may appear.

Figure 1 is a diagram of the system embodying my invention; 60

Figure 2 is an enlarged cross sectional view of the air spring showing the controlling valve and the operating element of the relay device; 65

Figure 3 is a cross-sectional view of the controlling valve operated by the relay device shown in the lower left hand corner of Figure 2:

Figure 4 is a longitudinal cross-sectional view of the pump cylinder; 70

Figure 5 is a diagram of a modification of my invention;

Figure 6 shows a cross-section of the master valve, the relay operating element and 75 the controlled valve used in the system of Figure 5;

Figure 7 illustrates a modification of Figure 5 in which a further relay operating element and valve are employed, the connection 80 between the relay element at the top of the well and the valve at the foot of the well being through a rod; and

Figure 8 is a diagram of a different modification of the system of Figure 5 in which a 85 relay and valve element is placed at the foot of the well and the relay element operated by compressed air conducted from the valve at the head of the well.

In the diagram of Figures 1 to 4 the pump 90 cylinder 1 is submerged in the water in the bottom of the well 2. This pump has a discharge pipe 3 which runs to the head of the well and is connected to the air spring 4 and to the distributing main 5 which distributing main leads in turn to the system and faucets such as shown at 130 in Figure 1 in a residence or the like. The main reservoir or tank 6 is charged with compressed air at the proper pressure and supplies air 100 to the pump cylinder 1 by way of the pipe 7, the pipe 8 and the controlling valve 9. The air spring comprises a tank or reservoir partly filled with water and partly filled with air at the proper pressure. The proper pressure of air is maintained by the reducer valve 10 in the pipe 11 which connects the tank 6 with the air spring 4. The air spring 4 is connected to the discharge pipe 3 and the delivery pipe 5 by means of the 110

T 12 and the short connection 13. The air spring 4 comprises a tank 15 having an annular screw socket member 16 at the upper end thereof for receiving a screw plug 17 which screw plug contains the master valve 18 and provides a connection for the pipe 11 by way of the port 19 communicating with the interior of the cylinder or tank 15. The valve 18 governs an admission port 20 and an exhaust port 21 and contains also a passageway 22 leading to the relay operating element 23 which consists of a pneumatic cylinder 24 and a piston 25. The valve 18 is connected by a stem 26 to a lever 27 pivoted upon the bracket 28. This lever 27 is operated by the float 30 through the following mechanism. A central supporting rod 31 extends from the lower surface of the plug 17 to a point adjacent the bottom of the tank 15. A bracket 32 is secured to this rod and a short lever 33 is pivoted thereupon. The lever 33 is connected at one end by means of the rod 34 with the float 30 and at the other end is connected to a transmission rod 35 which is connected to the outer end of the lever 27. The lever 33 is a first class lever and the lever 27 is a second class lever so that the motion of the float upward throws the valve 18 down upon its seat 20 and vice versa. The port 22 in the plug 17 is connected by way of the pipe 36 to the operating cylinder 24.

The pump 1 comprises a head member 37 and a foot member 38 between which is secured a barrel member 39. The head member has connection with the water discharge pipe 3 by way of the passage 40. This passage is connected at the center or axis of the pump with a pipe 41 inside the barrel 39. This pipe 41 extends down to the lower end of the barrel 39 where it is connected to a valve casing 42. The valve casing 42 contains a check valve 43 governing the flow of liquid between the pipe 41 and the interior of the barrel 39. Ports 44 lead from the lower part of the barrel 39 to the interior of the valve member 42. The valve casing 42 is connected by means of a central axial bolt 45 to the foot member 38 so that the head and foot members are securely clamped together. The foot member 38 has a valve passage 46 governed by the foot valve 47. These valve passages are covered by a conical screen 48 which prevents the entry of foreign matter into the pump barrel. The head member 37 has a connection for the short pipe 49 which connects with the union 50 to the controlling valve 9 as shown in Figure 3.

60 The union 50 is shown in section in Figure 3. It consists of a funnel shaped top portion 51 for guiding the threaded reduced portion 52 of the casing of the valve 9 into the threads of the union. The valve 9 comprises a cylindrical casing 54 having a

transverse exhaust outlet 55 leading to the valve port 56 at the lower end of the casing 54.

The upper end of the casing is closed by a cap member 57 which has an axial passage 58 therethrough terminating in an annular rim 59 which forms a valve seat governed by the movable valve member 60. The valve member 60 comprises an upper yielding seat 61 mounted upon a cylindrical barrel 62 and a lower yielding seat 63 mounted upon a central rod 64.

The barrel 62 has an annular ring 65 which embraces the stem 64. The stem 64 has a shoulder or flange 66 at its upper end. Thus the two parts of the valve have a lost motion between them. The valve 60 is secured by a grooved guide member 67 to the valve rod 68 which extends up through the pipe 8 and connects with the piston 25 in the cylinder 24. Near its upper end the rod 68 is connected to a small piston 69 fitting within a cylinder 70 formed as a continuation of the lower end of the cylinder 24. The space between the pistons 25 and 69 is open to the atmosphere through the port 71.

The operation of this system is as follows:

Assume that the tank 6 is properly filled with compressed air at the right pressure and that the pump 1 is submerged in the water of the well, when faucets of the distributing main 5 are opened the water will tend to flow out. This lowers the level of the water in the tank 15, as a consequence the float 30 drops, closing the exhaust valve passage 21 and opening the admission port or passage 20 to the pipe 36 and the relay operating cylinder 24. Air at the pressure prevailing in the tank 15 is thereby admitted to the cylinder 24 driving the piston 25 and rod 68 downward. Movement of the rod 68 downward opens the admission port 59 permitting compressed air to flow from the main tank 6 by way of the pipes 7 and 8 to the body of the valve 9 down to the interior of the pump 1 by way of the pipe 49, the water in the pump is then driven out by way of the discharge pipe 3 to the delivery main 5, part of the water being driven into the air spring 4, partially filling the tank 15. As the level of the water in the tank 15 rises the float 30 rises and moves the valve 18 down upon its seat closing the admission port 20 and opening the exhaust port 21. This permits the compressed air in the cylinder 24 to exhaust. The compressed air in the pipe 8 operating against the small piston 69 moves the piston and connected rod 68 upward closing the admission port 59 and opening the exhaust port 56. It can be seen that the piston 69 and rod 68 are free to move upward almost to the point of closing the admission port 59 before the exhaust port 56 is opened due to the lost motion connection between the two valves.

- It will be noted that the piston 25 is operated upon compressed air of the reduced pressure prevailing in the tank 15. The pressure prevailing below the piston 69 in 5 the pipe 8 is that of the tank 6. The areas of these pistons are proportioned to secure proper operation in opening and closing the controlling valve. The structure of the operating element 23 may be varied as may also 10 the structure of the controlling valve 9, except as these are made essential in the following claims. The structure of the float control valve may also be varied in the broader aspects of my invention as may 15 20 25 30 35 40 45 50 55 60 65 70 75 80 85 90 95 100 105 110 115 120 125 130
- which leads down to the pump, as shown in Figure 5, communicates either with the compressed air supply pipe 106 which leads to the tank 6 or it communicates with the exhaust opening 107 on the upper side of the diaphragm 97.
- The operation of this device is substantially the same as the previously described embodiment, the diaphragm 97 and double valve 100 serving as an operating element 75 and as a control valve, respectively, governed by the master valve 84. Assuming that the pump 1 is full of water and that the consumption system is opened as by opening a faucet, the level in the tank 15 drops causing the float 91 to assume the position shown in Figure 6. Air at the reduced pressure prevailing in the tank 15 passes through the port 85, passage 96, to the diaphragm chamber or cylinder 95, pushing the diaphragm 85 and piston upward and closing off the exhaust port 101 and opening the admission port 103 thereby permitting compressed air at tank pressure to pass through the pipe 106 to the pipe 75 and thence down to the pump. The air thus admitted drives the water out of the pump into the discharge main 3, part of the water going to the distributing main 5 and a part of the same going into the tank 15 to raise the level of the water therein.
- In Figures 5 and 6 I have illustrated a modified form of the invention. In this system the pump 1 is adapted to be submerged in the water at the bottom of the well 2, the pump having a water discharge pipe 3 connected with the air spring 4 and with the distributing main 5. The pump also has an air pipe 75 running from the control valve 76 down to the head of the pump. The control valve 76 is mounted directly upon the plug 77 which is adapted to be screwed into the annular socket 78 at the top of the tank 15.
- The plug 77 bears upon its lower surface a supporting rod 79 to which is pivoted at the point 80 a bell crank operating lever 81, the one arm of which lever 81 is connected to a collar 82 on the valve stem 83 of a movable valve 84 having an admission port 85 and an exhaust port 86. This valve I term the master valve. The opposite end of the bell crank lever 81 is connected by a pin 87 to a spring 88, the other end of which spring is connected to a pin 89 on the float lever 90. The float lever 90 comprises a bell crank lever bearing the float 91 on the one arm and the pin 89 on the other arm. To prevent the float from carrying past center a stop 92 and pin 93 on the lever and on the supporting arm 79 respectively are provided. It can be seen that the combination of the two bell crank levers and the spring 88 provides a snap operating mechanism for the valve 84. The plug 77 bears a diaphragm chamber 95, the interior of which communicates with the valve ports 85 and 86 by way of the valve passage 96. A diaphragm 97 having a piston member 98 closes off the diaphragm chamber 95. The piston 98 is connected by means of a stem 99 with a double valve structure 100 having an exhaust port 101 served by the movable valve member 102 and an admission port 103 served by the movable element 104. A spring member 105 in the cage of the valve 76 tends to hold the valve 100 in such position as to close off the admission port 103. The pipe 75
- When the level of water in the tank 15 has risen to the proper point the float 91 will rise far enough to throw the operating lever 81 to the other side of the center, thereby shifting the master valve 84 to open the exhaust port 86 and close the admission port 85. As the air escapes through the exhaust port 86, the spring 105 moves the double valve 100 downward, closing off the admission port 103 and opening the exhaust port 101. This permits the air in the pipe 75 and in the pump 1 to escape. At the same time the pump 1 fills with water from the well.
- It can be seen that the water in the tank 15 forms an artificial level which varies with the amount of water discharged from the pump 1, that is to say, the level rises and falls with each stroke of the pump. The float control valve mechanism comprises means responsive to this artificial level for operating the admission and exhaust valves of the pump in accordance therewith for controlling the individual strokes of the pump.
- In Figures 7 and 8 I have indicated diagrammatically modifications of the system shown in Figure 5 in which a further relay control valve is employed for operating a control valve located in the well near the pump. These relay mechanisms are employed particularly where the well is deep and the capacity of the pipe 75 would be so great as to entail a noticeable loss by the

exhaust of the quantity of air which this pipe would contain. It can be seen with each stroke of the pump the cubical contents of the pipe 75 are lost by opening of the exhaust.

In the diagram of Figure 7 a cylinder 110 and an operating piston 111 are employed to operate the valve 112 near the pump 1 at the foot of the well. This valve comprises a movable valve body 113 serving an admission port 114 and an exhaust port 115. The movable valve body 113 is connected through the piston 111 by means of rod 116. The relay cylinder 110 is in this form connected to the controlling valve 76 by means of the pipe 75' instead of the pipe 75, as shown in Figure 5. Compressed air is conveyed from the tank 6 by way of the pipe 117 and 118 to the controlling valve 112.

It is also obvious that instead of using a solid rod 116 a column of liquid might be employed or the operating element might be located at the foot of the well and operated by compressed air. In Figure 8 I have shown the operating cylinder 118' located at the foot of the well adjacent the pump 1 for operating the movable valve element 119 which controls a valve passage 120. The movable piston 121 bears a yielding face 121' adapted to engage the seat 120 closing off the exhaust port 123 when the passage is opened.

The pipe 124 is adapted to convey air from the control valve 76 being connected in place of the pipe 75 shown in Figure 5. The pipe 125 is adapted to convey compressed air at the pressure of the tank 6 to the valve 119 and thus to the pump 1.

It is apparent that the invention may appear in other forms and may be used for other purposes.

I claim:

1. In combination a single cylinder pneumatic displacement pump having inlet and discharge check valves for liquid, a normally closed faucet controlled pressure delivery system connected to the pump through said discharge check valve, a source of compressed air, said delivery system comprising a chamber for maintaining a variable level of liquid under pressure sufficient to stall the pump when the delivery system is closed, a control valve for governing admission and exhaust of motive fluid to and from the pump for each stroke and means moving with said variable level governing said control valve.

2. In combination, a single cylinder pneumatic displacement pump adapted to be submerged in the water in the well, a normally closed faucet controlled delivery system connected to said pump, a source of compressed air for operating the pump and a float valve at the head of the well for con-

trolling the individual strokes of the pump by admitting compressed air to and exhausting the same from the pump cylinder, said delivery system being adapted to deliver the water to outlets lying a substantial distance above the float valve.

3. In combination, a single cylinder pneumatic displacement pump adapted to be submerged in the water in the well, a normally closed faucet controlled delivery system connected to said pump, a source of motive fluid for operating said pump, a controlling valve for controlling each stroke of the pump, said valve being located at the head of the well and level controlled means at the head of the well for governing said valve means, said delivery system being maintained under sufficient pressure to deliver water to outlets lying a substantial distance above said level controlled means.

4. In combination, a single cylinder pneumatic displacement pump adapted to be submerged in the water at the bottom of the well, a normally closed faucet controlled delivery system connected to said pump, means for maintaining a water level at the head of the well responsive to the individual stroke of the pump and valve means controlled by the variations in water level at the head of the well for controlling the admission of motive fluid to the pump cylinder at the foot of the well, said delivery system being maintained under pressure suitable to deliver water to outlets lying a substantial distance above the water level at the head of the well.

5. In combination, a single cylinder pump adapted to be submerged in the liquid to be pumped, a source of compressed air, an air spring, a pipe connecting the pump and the air spring, a valve having a float controlled element in said air spring, said valve controlling the admission and exhaust of air to and from the pump.

6. In combination, a single cylinder pump adapted to be submerged in the liquid to be pumped, a tank communicating with said pump, a supply main communicating with the tank and the pump, means for maintaining a pressure in said tank invariably above atmosphere, a float controlled element in said tank, a master valve controlled by said float and a control valve controlling the admission and exhaust of the pump governed by said master valve.

7. A single cylinder pump adapted to be submerged in the liquid to be pumped, a compressed air tank a tank serving as an air spring, a connection between the pump and the air spring tank, a distributing system communicating with the air spring, said air spring being supplied with compressed air at a reduced pressure, a float in said tank, a master valve controlled by said float, a re-

5 lay operating element controlled by air at reduced pressure from the air spring tank and a controlling valve governed by said operating element for controlling the admission and exhaust of compressed air to and from the pump.

8. In combination, a pump, a source of motive fluid, a discharge pipe, a distributing main, an air spring tank connected to 10 said pipe and said main, a valve body closing off the top of the tank, means for supplying said tank invariably with motive fluid at reduced pressure, a valve in said valve body and a float in the tank controlling 15 said valve, and means operated by the compressed air at reduced pressure and controlled by said valve for governing the individual stroke of the pump.

9. In combination, a source of motive 20 fluid, an air spring tank having an opening at the top of the same, a valve body comprising a plug for closing said top, said valve body having a communicating opening therethrough for maintaining motive fluid, 25 at a predetermined pressure invariably higher than atmosphere in the tank, an unobstructed connection at the bottom of the tank for admitting water under pressure, a supporting rod connected to the bottom of said 30 valve body and depending into the tank, a float movably mounted with respect to said supporting rod and a valve element in the valve body movable in response to the movement of said float.

35 10. In combination, a source of motive fluid, a tank having an opening at the top, a plug for closing said opening, said plug comprising a valve body, a passage through said plug for providing motive fluid, a valve 40 stem projecting from the valve body to the interior of the tank, an exhaust passage, a cylinder passage, a passage between the interior of the tank and said valve body, said last passage comprising an admission passage, said exhaust and said admission passages being controlled by the valve in said valve body, and a separate pump cylinder controlled by said valve.

11. In combination, a pump adapted to 50 be submerged in the water at the bottom of the well, an air controlling valve for said pump at the foot of the well near the pump, an air spring at the head of the well, said air spring being constantly maintained under pressure to smooth out the discharge between strokes of the pump, a discharge pipe connecting the pump and the air spring, a delivery main communicating with the discharge pipe and the air spring, an operating element for the control valve at the head of the well, and a float controlled valve governed by the variations of level of water in 55 the air spring for controlling the operation of said operating element.

12. In combination, an air spring tank, 65 said tank being constantly maintained under pressure, an opening at the top of the tank, a plug for said opening, said plug having a supporting rod connected to the lower surface thereof, a float movable on said supporting rod, said plug comprising a valve, a diaphragm chamber mounted on said plug, a control valve connected to said diaphragm chamber, a movable valve element controlled by the diaphragm in said chamber, and 75 means controlled by said last named valve for varying the water level in said tank.

13. In combination, a tank, said tank being constantly maintained under pressure, a valve body at the top of the tank, a supporting rod connected to said valve body and projecting down into the tank, a float movably mounted on said supporting rod, a valve in said valve body, and means controlled by 80 said valve for varying the level of water in 85 said tank by the introduction of liquid thereto, said valve being controlled by said float.

14. In combination, a tank, said tank being constantly maintained under pressure, 90 a valve body mounted at the top of said tank and having a supporting rod projecting into the tank, a movable float member supported on said rod, a valve in said valve body, a diaphragm chamber having a 95 diaphragm mounted on said valve body, said valve controlling the admission and exhaust of motive fluid to said diaphragm chamber, and a control valve governed by the movement of said diaphragm. 100

15. In combination, a pump, a discharge pipe comprising a faucet controlled delivery system, a source of motive fluid, an air spring having unrestricted communication with the pump, a valve governing the effective application of the motive fluid to the pump for each stroke, and a float subject to the level of the water in the air spring governing said valve, said delivery system being maintained under sufficient pressure at 110 all times to deliver water to outlets a substantial distance above the level in the air spring. 105

16. In combination, a single cylinder pump, a source of motive fluid, a discharge 115 pipe invariably under pressure, an air spring communicating at all times with the discharge pipe, a float in the air spring, and valve means governed by the float for governing the effective application of the motive 120 fluid to the pump for each stroke thereof, said delivery system being maintained under sufficient pressure at all times to deliver water to outlets a substantial distance above the level in the air spring. 125

17. In combination, a pump, a source of motive fluid, a delivery system, an air spring connected with the delivery system, a re-

- ducing valve between the source of motive fluid and the air spring, a float in the air spring, a motor operated by said reduced pressure and controlled by said float, and a valve governed by the motor to control effective application of motive fluid from said source to said pump at each stroke thereof.
18. In combination, a single cylinder pump, a source of motive fluid, a faucet controlled delivery system connected to said pump, an air spring for smoothing out the flow in the delivery system between strokes of the pump, a reducing valve between the source of motive fluid and said air spring, a float in said air spring, a motor operated by reduced pressure prevailing in said air spring, said motor being controlled by said float, and a main valve for the pump governed by the motor to control the effective application of the fluid to the pump at each stroke thereof.
19. In combination, a source of motive fluid, a pump, a faucet controlled delivery system, an air spring connected to said system, said air spring being constantly under pressure, a float in said air spring, a controlling valve for the pump for controlling the effective application of motive fluid thereto, said valve being located in the well adjacent the pump, a motor element at the head of the well controlled by said float in the air spring, and a connection between said motive element and said valve.
20. In combination, an air spring tank, said tank being constantly maintained under pressure, an opening at the top of the tank, a plug for said opening, said plug having a supporting rod connected to the lower surface thereof, a float movable on said supporting rod, said plug comprising a valve, a motor chamber having a movable element, a control valve governing said motor chamber, a movable valve element controlled by the movable motor element, and means controlled by said last named valve for varying the water level in said tank.
21. In combination, a tank, a valve body mounted at the top of said tank and having a supporting rod projecting into the tank, a movable float member supported on said rod, a valve in said valve body, a motor chamber having a motor element in said chamber, said valve controlling the admission and exhaust of motive fluid to and from said motor chamber, and a control valve governed by the movement of said movable element.

In witness whereof, I hereunto subscribe my name this 20th day of July A. D. 1917.

BURTON S. AIKMAN.
